CENTRALIZED TRAFFIC CONTROLLING
SYSTEM FOR RAILROADSSedgwick N. Wight, Rochester, N. Y., assignor to
General Railway Signal Company, Rochester,
N. Y.

Application July 22, 1941, Serial No. 403,526

12 Claims.

(Cl. 246—3)

The present invention relates to centralized traffic controlling systems of the code type and more particularly to the indication portion of such systems for transmitting indications from field stations to a central office.

In centralized traffic control systems of the code type an operator or dispatcher at a central office controls the track switches and signals at various points on a railway system extending as much as one hundred miles in one direction from a central office, and in order for the operator to control such switches and signals he must, of course, be informed as to the locations of the trains, the positions of switches, and the indicating conditions of signals. In a system of the type just referred to, a considerable amount of time is required for the transmission of a single control code from the office to a field station and also for the transmission of an indication code from the field station to the office, and in the larger systems, in view of the large number of indications required, it is quite common for the system to get overloaded, that is, more codes are required to be transmitted in a particular period of time than the system can handle, which means that trains will be delayed by reason of the improper indications of signals, the locations of trains, and the positions of switches.

In accordance with the present invention it is proposed to take advantage of the positions of switch levers and signal levers to inform the operator as to the positions and conditions of such switches and signals. It is, of course, understood that in the great majority of instances the switch will immediately follow a change in the position assumed by the switch lever and a signal will immediately follow the change in the position of its associated signal lever, but the position of the switch lever or signal lever may not be entirely relied upon to give an indication of the actual position of the switch or condition of the signal in the field. This is true because there are times when a switch will not follow the change in the position of its switch lever even though the proper code is transmitted to the field. This, for instance, might be due to an obstruction between the switch points or by reason of the presence of a train on the approach section to the track switch which would prevent its operation. Similarly, a signal will not necessarily assume the clear condition in response to the transmission of a signal-clear code, because the track section directly in advance of such signal may be occupied by a train. In accordance with the present invention it is proposed to provide means whereby

if a track switch does not assume a position in correspondence with the position of its control relay, within a predetermined period of time after such control relay has been operated, this period of time being long enough to allow the slowest switch to operate from one position to another, an out-of-correspondence indication code will be transmitted to the office to light an out-of-correspondence indication lamp associated with that switch machine lever. With this out-of-correspondence indication lamp lighted, the operator will know that the switch assumes a different position than does the switch control lever. If, on the other hand, the out-of-correspondence indication lamp is not lighted, the operator may rely upon the position of the switch control lever as an indication of the position assumed by the actual track switch at the field location. What has just been said about the switch control lever and its associated out-of-correspondence indication lamp is also true of the signal control lever if an individual out-of-correspondence indication lamp is provided for such signal control lever, as may be done, if desired.

Another object of the present invention resides in the provision of a single out-of-correspondence indication lamp for indicating when any one of a plurality of signals or the track switch at a particular field station is out of correspondence with its control relay, if desired.

Another object of the present invention resides in the provision of means for extinguishing an out-of-correspondence indication lamp local to such lamp when the associated control lever has been operated to a new position.

Another object of the present invention resides in the provision of means for restoring the out-of-correspondence code transmitting means at a field station to its normal condition after it has manifested an out-of-correspondence condition, such restoration being accomplished by the transmission of a new control code to that field station.

Other objects, purposes and characteristic features of the present invention will in part be pointed out hereinafter and in part be obvious from the accompanying drawings in which:

Fig. 1 shows the invention applied to any one of a plurality of field stations for the purpose of indicating an out-of-correspondence condition between the switch control lever and the track switch which it controls; and

Figs. 2A and 2B illustrate, when laid end to end, the invention applied to any one of a plurality of field stations to indicate if an out-of-corre-

spondence condition exists between any one of four signals and their respective control relays or between the associated track switch and its control relay.

In order to simplify the illustration and description of the present invention, it has been shown applied to the code type centralized traffic controlling system illustrated in the patent to Judge et al., No. 2,082,544, as modified in the patent to Hailes et al., No. 2,229,736. It should, however, be understood that the invention may also be applied to a centralized traffic controlling system of the two-line wire code type such as illustrated in the application of Hailes et al., Ser. No. 197,404, filed March 22, 1938, which has been issued as Patent No. 2,259,561, dated October 21, 1941, as well as to the four-line wire type code system illustrated in the patents to Judge et al., No. 2,082,544, and Hailes et al., No. 2,229,736, above referred to.

Referring to Fig. 1 of the drawings attention is directed to the fact that those portions of the drawings shown in light lines comprise portions of Fig. 1 and Fig. 3A of the patent to Hailes et al., No. 2,229,736; whereas, the wires and parts shown in heavy lines are those features of the system that must be added to comprise the system of the present invention. Also, referring to Fig. 2A and Fig. 2B of the drawings it should be understood that the apparatus illustrated in Fig. 2A in light lines corresponds to a portion of the apparatus illustrated in Fig. 1 of the Hailes et al. patent and that the apparatus illustrated in light lines in Fig. 2B of the drawings corresponds to all of the apparatus illustrated in Fig. 3B of this same patent to Hailes et al., No. 2,229,736; whereas, the portions illustrated in heavy lines comprise a modified form of the present invention superimposed thereon. In view of the fact that the communication system to which the present invention is applied is fully described in the patents to Judge et al. and Hailes et al. only a brief discussion of this portion of the apparatus will be given so that the greater portion of the specification may be used to describe the features of the present invention.

In a centralized traffic controlling system of the type contemplated by this invention, the switches and signals at various points along a railroad are placed under the control of an operator in a central control office, in such a way that the operator may at will change the position of the switches subject to automatic approach and detector locking circuits which prevent unsafe operation of any switch, and in such a way that the operator may at will hold at stop any of the signals or allow them to clear dependent upon the position of the associated switches and the location of trains within certain track sections in advance, so that the signals will indicate proceed only when it is safe for the passage of traffic. Also, the system provides means whereby indications are displayed in the control office to inform the operator of the presence or absence of trains on various track sections throughout the territory under his supervision. A particular feature of the present invention resides in the provision of means to show that a traffic controlling device has not been operated into correspondence with its control relay within a predetermined period of time.

The switches and signals of a railroad system are not usually evenly distributed throughout the system, but some are located near or adjacent

to each other while others are at considerable distances. That apparatus located within a limited area determined by the convenience and economy with which the apparatus may be interconnected by direct control wires, is conveniently termed a field station. A code type selective communication system is then provided to interconnect the control office with the several outlying field stations for the transmission of controls and indications to and from these field stations.

This code selective type communication system requires only a small number of line wires to establish communication between the control office and a large number of field stations with means providing for the transmission of a large number of controls and indications for each of the field stations. The system illustrated is of the two circuit type having a control line circuit and an indication line circuit, which circuits are made up by the provision of at least three line wires, one control line wire, one indication line wire and a common return line wire. In the illustrations, however, the control line is provided with an individual return line, and similarly, the indication line is provided with an individual return line. However, if desired, a single circuit two-wire communication system such as illustrated and described in the patent to Hailes et al., Patent No. 2,259,561, dated October 21, 1941, may, if desired, be employed in practicing the present invention.

Communication is established between the control office and the several field stations by the transmission of suitable codes, which cause the selector type apparatus at each location to operate step-by-step through cycles of operation. The system upon which the present invention is superimposed is of the station selective coded duplex type, wherein controls and/or indications may be transmitted during any particular operating cycle of the system.

For the transmission of controls, a series of impulses of selected polarities is placed upon the control line circuit. The apparatus at the control office and at a field station is operated through a cycle of operation for each series, irrespective of the character of the impulses of the series, while the character of the impulses of each series determines the particular station selected for that cycle and the controls transmitted to that selected station.

For the transmission of indications, a series of impulses is placed upon the indication line circuit, which impulses set up distinctive conditions by reason of their presence or absence on the steps of each cycle, these steps being marked off by impulses placed upon the control line circuit.

With such an arrangement, whenever a cycle of operation occurs for the transmission of indications alone, then the series of impulses placed upon the control line circuit for causing the step-by-step operation must be of such a character as not to select any field station, but to merely cause the step-by-step operation at that field station when transmitting its indications. Similarly, whenever a cycle of operation occurs for the transmission of controls alone, then there are no impulses placed upon the indication line circuit, thereby setting up distinctive conditions which form a code, and this code is not employed by any field station, so as to prevent the false registration of a station when it is not transmitting indications.

For the purpose of simplifying the illustrations and facilitating in the explanation, the various parts and circuits constituting the embodiment of the invention have been shown diagrammatically and certain conventional illustrations have been employed, the drawings having been made more with the purpose in mind of making it easy to understand the principles and mode of operation, than with the idea of illustrating the specific construction and arrangement of parts that would be employed in practice. Thus, the various relays and their contacts are illustrated in a conventional manner, and symbols are used to indicate connections to the terminals of batteries, or other sources of electric current, instead of showing all of the wiring connections to these terminals. Also the coding apparatuses have been shown conventionally by dotted rectangles.

The symbols (+) and (−) are employed to indicate the positive and negative terminals respectively of suitable batteries, or other sources of direct current; and the circuits with which these symbols are used, always have current flowing in the same direction. The symbols (B+) and (B−) indicate connections to the opposite terminals of a suitable battery, or other direct current source which has a central or intermediate tap designated (CN); and the circuits with which these symbols are used, may have current flowing in one direction or the other depending upon the particular terminal used in combination with the intermediate tap (CN). When alternating current is used in place of direct current, the particular symbols employed represent the relative instantaneous polarities.

Communication system generally.—The general plan of organization of a system contemplated upon which the present invention is superimposed may be best understood by referring to Pat. No. 2,082,544. It is to be understood, of course, that the system may be extended so as to provide as many field stations as necessary to govern the territory placed under the supervision of the operator in the control office, but for convenience in describing the present invention, only one field station has been shown in each of Figs. 1 and 2.

A control line wire 10 extends from the control office to the first field station, from the first field station to the second field station, and so on to the end of the system where it is connected to the control line return wire 12 which extends from the control office through each of the field stations. Similarly, an indication line wire 14 extends from the control office to the first field station, from the first field station to the second field station, and so on, to the end of the system where it is open ended. Associated with this indication line wire 14 is an indication line return wire 16 which extends from the control office through the several field stations and to which the indication line is connected at that particular field station selected for the transmission of indications during a cycle of operation, as more specifically explained in Patent No. 2,082,544. Although a four wire system has been shown for convenience in illustrating one embodiment of the present invention, it is to be understood that one common return wire may be used in place of the two return wires 12 and 16. In other words, the system may be termed a two line circuit system which circuits may be combined in any suitable manner, such as by the provision of a single common return wire, thereby making a three line wire system, or by both line circuits superimposed upon two line wires by employing distinctive cur-

rents such as direct current and alternating current, or by the use of two frequencies which do not have common harmonics. Also, if desired, a two line wire system such as shown in the patent to Hailes et al., Patent No. 2,259,561, dated October 21, 1941, may be employed. Energy for the control line circuit is supplied from a control battery in the control office with the particular polarity selected by pole changing contacts located on code sending relays controlled by wires PC and NC respectively (see Figs. 1 and 2A). These wires correspond respectively to wires 47 and 48 in Fig. 5 of the above mentioned patent to Judge et al., and it is illustrated in Fig. 4 of that patent how the pole changing contacts of the code sending relays control the polarity of the control line circuit. When the code sending relay connected to wire PC is energized, a positive impulse is placed on the control line circuit, but when the code sending relay connected to wire NC is energized, a negative impulse is placed upon the control line circuit. With both the code sending wires energized or deenergized the control line circuit is maintained deenergized. Whenever energy is applied to the control line circuit by the code sending relays, such energization is broken up into time spaced impulses by the periodic operation of the stepping apparatus.

The indication line circuit includes message relays in its two branches in the control office and includes pulsing contacts in the corresponding branches at each field station. As corresponding branches are selected at the control office and at each field station when the control line circuit is energized closing front contacts on the repeating relays for the control line circuit, and as corresponding branches are connected in series during the deenergized condition of the control line circuit as repeated at the control office and at each field station by the closure of suitable back contacts, these two branches of the indication line circuit at the control office and at each field station may be conveniently termed front and back branches. In the control office, a message relay is included in the back branch, and similarly, a message relay is included in the front branch of the indication circuit, all as clearly illustrated in Figs. 4 and 6 of the Judge et al. patent above referred to.

Structure of Fig. 1.—Referring to Fig. 1 of the drawings the coding apparatus employed in the office has been shown by dotted rectangles designated "Office coding apparatus." The switch machine lever 6SML and the starting button 6SB correspond to like apparatus shown in Fig. 5 of the Judge et al. Patent No. 2,082,544; whereas, the track occupancy indicating relay 6IRB, its contact 232, the indicating lamp 6OS and the station relay 6ST correspond to like designated devices illustrated in Fig. 6 of this Judge et al. patent. The apparatus shown in the right-hand portion of Fig. 1 of the drawings, that is, at the field station of the system shown corresponds as to the track switch 6TS, the switch machine 6SM, the switch machine control relay 6WR and 6WN, the detector track relay 6TR, the switch repeating relay 6WP to like apparatus illustrated in Fig. 3A of the Hailes et al. patent, No. 2,229,736. The change relay 6CH and its associated contacts 22 and 154, and the detector track relay 6TR and its associated contacts 21 and 192 correspond to like relays and contacts illustrated in Fig. 3 of the Judge et al. Patent No. 2,082,544.

The wires shown in heavy lines as well as the 75 out-of-correspondence indication relay 6OCR, the

indicating lamp 6OCL, the thermal relay 6TE and the out-of-correspondence transmitting relay 6TER have been added as a part of the present invention as it is applied to the disclosure of the above-mentioned Hailes et al. and Judge et al. patents.

Operation of Fig. 1 structure.—In order to point out how the structure which was added to the disclosures of the patents to Hailes et al. and Judge et al. performs new functions, certain operations of the entire system will be described from which the new functions and the apparatus which produces them may be readily understood. Let us assume that the operator in the office shown at the left-hand end of Fig. 1 of the drawings desires to operate the track switch 6TS shown in the right-hand portion to the reverse or take-siding position and in order to do so moves the switch machine lever 6SML from its right-hand position to its left-hand position and then depresses the starting push button 6SB. Depression of the starting button 6SB will initiate the coding apparatus into operation and will transmit a station call code consisting of current impulses of positive and negative polarity over the control wires 10 and 12 to the field station illustrated at the right-hand end of Fig. 1 of the drawings. This station code call will then pick up a station relay (not illustrated but comprising a part of the illustrated field coding apparatus) which will connect the various control relays at that field station to the field coding apparatus through contacts of stepping relays. The second part of the code will have impulses of positive and negative polarities depending upon the position assumed by the switch control lever 6SML which second part will be different than the code portion that would have been transmitted if the switch machine control lever had not been moved, this by reason of the fact that the circuit including the wire NC has been closed and the circuit including the wire PC has been open by this operation of the switch control lever 6SML.

The code that is transmitted to the field station (lever 6SML to the left) is such as to momentarily complete an energizing circuit for the reverse switch control relay 6WR. The picking up of this relay 6WR will, at its back contact 350, open the stick circuit for the normal switch control relay 6WN and will at its front contact 350 close a stick circuit for the relay 6WR including the back contact 351 of the normal switch control relay 6WN. Also, the picking up of the relay 6WR and the dropping of the relay 6WN will close a switch machine reversing circuit including back contact 352 of the relay 6WN and front contact 353 of the relay 6WR. The moment that the switch machine is energized and unlocked the switch machine repeater relay 6WP is deenergized and its neutral contact finger moves to retracted position. Two circuits are, therefore, closed for the heating element of the time element device 6TE. This time element device 6TE may be of any suitable construction but as illustrated comprises a relay of the thermal bimetallic type including a heating coil which if heated will cause the closure of its contacts 354 after the lapse of a predetermined period of time after such heating began. These two circuits may be traced as follows: (1) Beginning at the terminal (+) of a suitable source of current, back contact 355 of relay 6WN, front contact 356 of the relay 6WR, polar contact 357 of the relay 6WP assuming its right-hand position, through the heating coil of

the thermal relay 6TE and through back contact 358 of the out-of-correspondence transmitting stick relay 6TER, and (2) a similar circuit which, however, includes back contact 355 of the relay 6WN and back contact 359 of the switch repeating relay 6WP. Under normal conditions the switch machine 6SM will be operated to its new or reverse position before the contacts 354 of the thermal relay 6TE close. If we assume this to be the case, it will be seen that both of the circuits above mentioned will be opened. The first mentioned circuit will be opened by movement of the polar contact 357 of the switch repeating relay 6WP to its left-hand position and the second mentioned circuit will be opened by the opening of back contact 359 of the switch repeating relay 6WP. Since both of these circuits have now been opened the thermal time element relay 6TE may again cool and will, therefore, not have performed the function of picking up the out-of-correspondence transmitting relay 6TER.

Let us now assume that the track switch 6TS was attempted to be operated as before, but was jammed as by a lump of coal which did not allow the switch machine 6SM to complete its operating stroke. Under this assumed condition the switch machine repeater relay 6WP will remain in its deenergized position with its polar contact 357 in its right-hand position. The assumed condition is with the relays 6WR and 6WN energized and deenergized respectively, and with the track switch jammed. Under this condition both of the energizing circuits heretofore traced for the thermal time element relay 6TE will remain closed. After the lapse of a predetermined period of time the contacts 354 of the thermal relay 6TE will close, thereby closing a pick-up circuit for the out-of-correspondence transmitting relay 6TER which may be readily traced and which includes both of the two circuits for the time element relay 6TE heretofore traced and further including the contact 354 of this relay 6TE. The completion of this circuit causes the relay 6TER to be picked up, which relay is then stuck up through two stick circuits for the relay 6TER each including the stick contact 358 of this relay 6TER, one of which stick circuits includes the right-hand polar contact 357 of relay 6WP through front contact 356 of relay 6WR and the back contact 355 of relay 6WN; whereas, the other stick circuit includes the back contact 359 of the relay 6WP and the back contact 355 of the relay 6WN. The picking up of the relay 6TER momentarily breaks the stick circuit for the change relay 6CH at the back and front contacts 360 of the relay 6TER, since this momentary opening of the contact 360 occurs at a time when the shunt around this contact, and including the contacts 361 and 362 of the relay 6WP and front contacts 363 and 364 of the relay 6WR and 6WN respectively, is open. The change relay 6CH will be actually momentarily deenergized and will assume its retracted position until a code has been transmitted from that field station. The dropping of the change relay 6CH by reason of the closure of its back contact 154 will initiate the communicating system into operation, assuming that the system was at rest. With the front contact 366 of the relay 6TER closed an out-of-correspondence code portion preceded with a station selecting code portion will be transmitted to the central office over the indication wires 14 and 16. The station selecting portion of this code will result in the energization of the station selecting relay 6ST in

the office, all in a manner as clearly described in the patent to Judge et al., No. 2,082,544. With the station selecting relay 6ST now momentarily energized and with its front contacts 231 and 368 closed the out-of-correspondence relay 6OCR is operated to its right-hand position by reason of the fact that front contact 366 of the relay 6TER at the field station was then closed at the time a code was transmitted, resulting in the transmission of the proper code. The indication relay 6IRB will also be operated to its right-hand circuit closed position or to its left-hand circuit open position to either light the OS lamp 6OS, or extinguish the same depending upon whether the detector track relay 6TR is then deenergized or energized. The operation of the out-of-correspondence relay 6OCR to its right-hand position will by the closure of its polar contact 369 cause illumination of the out-of-correspondence lamp 6OCL. This will inform the operator that the track switch 6TS does not assume its take-siding position which the switch machine control lever 6SML, which now assumes its left-hand position, calls for.

Let us now assume that the operator desires to return his switch to the normal position on the theory that there is no particular advantage in having a track switch assume an intermediate position and that the operator to do so now returns his switch control lever 6SML to its normal right-hand position. Let us also assume that he depresses the start push button 6SB and that this results in the immediate transmission of a code to the field station which will cause the normal switch control relay 6WN to be energized. The normal relay 6WN will, of course, assume its energized position before the reverse switch control relay 6WR assumes its deenergized position, because it is the picking up of the relay 6WN that by the opening of its back contact 351 results in the dropping of the relay 6WR. During this transition the back contacts 355 and 356 of the relays 6WN and 6WR, respectively, are both open, thereby causing a momentary break in the stick circuit for the out-of-correspondence transmitting relay 6TER, thereby causing this relay 6TER to again return to its normal deenergized position. Since during this transition, namely when the relay 6WR and 6WN both assume their deenergized position, the switch repeater relay 6WP is still assuming its deenergized position and has its front contact 361 open, the contact 360 of the relay 6TER is shunted and moves from its front to its back position. The dropping of contact 360 of relay 6TER while unshunted, of course, results in the deenergization and dropping of the change relay 6CH (this change relay having in the meantime been picked up by suitable means contained in the field coding apparatus) thereby again initiating the coding apparatus into operation at a time when the front contact 366 of the relay 6TER is open. The code now transmitted to the central office will be of a character (contact 366 being open) to operate the out-of-correspondence relay 6OCR back to its normal left-hand position if it is not already assuming that position. In practice, however, the relay 6OCR would have already assumed the left-hand position, because of closure of a local circuit which was closed by the operation of the switch machine lever 6SML to its right-hand position for the purpose of returning the track switch to its normal position. This local circuit is closed when the switch machine lever 6SML assumes its middle position and may

be traced from the terminal (—) through the contact 370 of the lever 6SML and through back contact 368 of the station selecting relay 6ST. In other words, every operation of the switch machine control lever 6SML to a new active position will result in the deenergization of the out-of-correspondence lamp 6OCL if then lighted. Furthermore, if an indication is sent in from the particular field station at which the relay 6TER is located and this relay 6TER is then in its retracted position, a code will be transmitted to the office which will result in the operation of the out-of-correspondence relay 6OCR to its left-hand position, resulting in the indicating lamp 6OCL being extinguished.

It has just been assumed that the operator after making an attempt to operate the switch 6TS to its reverse position, which was unsuccessful, and then returned his lever to the normal position. It was observed that due to the fact that the switch control relay 6WN picked up before the switch control relay 6WR dropped that the stick circuits for the relay 6TER were momentarily broken, to cause this relay 6TER to assume its deenergized position. Let us now assume that the track switch 6TS could also not be returned to its normal position. If this is the case the thermal relay 6TE will again be energized through a circuit including back contact 356 of the relay 6WR and back contact 359 of the relay 6WP and if this were to prevail for said predetermined period of time the thermal relay 6TE would close its front contact 354 thereby again picking up the out-of-correspondence transmitting relay 6TER. This would, of course, result in the dropping of the change relay 6CH and in the transmission of an out-of-correspondence code to the central office due to the fact that front contact 366 of the out-of-correspondence relay 6TER is then closed. This code would, of course, again illuminate the out-of-correspondence lamp 6OCL and would inform the operator that the track switch 6TS is out of correspondence with the switch machine control lever 6SML. It is readily seen that closure of back contact 359 of the switch repeating relay 6WP manifests that the switch machine is unlocked. It is also readily seen that the contacts 355, 356, and 357 in combination constitute out-of-correspondence contacts to establish a circuit which is closed when non-correspondence exists. It is also readily seen that the contacts 363, 364 and 362 of the relays 6WR, 6WN and 6WP constitute in combination the correspondence contacts which close branch circuits only when correspondence between these switch control relays and switch repeater relays exists and that these branch circuits during correspondence conditions shunt the contact 360 of the out-of-correspondence transmitting relay 6TER.

Structure of Fig. 2.—The switch control lever 8SML, signal control lever 4—5SGL, starting push button 8SB and the office coding apparatus correspond to like apparatus shown in Fig. 1 of the Hailes et al. Patent No. 2,229,736; whereas, the station selecting relay 8ST its associated contact 231, the indication relay 8IRB, its associated contact 232 and the track occupancy lamp 8OS correspond to similar devices of Fig. 6 of the Judge et al. Patent No. 2,082,544. All of the apparatus and circuits illustrated in light lines in Fig. 2B of the drawings except the change relay 8CH correspond to like devices shown in Fig. 3B of the Hailes et al. Patent No. 2,229,736, the change relay 8CH and its associated contacts 22

and 154 correspond to a like designated relay shown in Fig. 3 of the Judge et al. Patent No. 2,082,544. The apparatus and circuits shown in heavy lines in Fig. 2B comprise the apparatus and circuits which are superimposed upon the structure of the Hailes et al. and Judge et al. patents to constitute the present invention.

Referring to Fig. 2B of the drawings, this figure of the drawings illustrates a short section of track including the end of a passing siding connected to the main track by a track switch 8TS. This track switch is operable by a switch machine 8SM and has associated therewith east-bound starting signals 4A and 4B and west-bound entering signals 5A and 5B. These signals comprise part of an absolute-permissive-block signalling system including a directional stick relay 4S, home-distant relays 4H and 5AH and associated track relays 7TR and 8TR. The switch machine 8SM which operates the track switch 8TS is controlled by switch control relays 8WR and 8WN; whereas, the signals 4A, 4B, 5A and 5B are controlled by signal relays 4AG, 4BG, 5AG, 5BG, which signal relays are in turn controlled by code controlled signal control relays 4GZ, 5GZ and 4-5B and by correspondence relays 8RCR and 8NCR. As in the Fig. 1 structure the apparatus includes a thermal time element relay 8TE and an out-of-correspondence transmitting relay 8TER. The change relay 8CH corresponds to the change relay CH¹ shown in Fig. 3 of the Judge et al. patent above referred to.

Operation of Fig. 2 structure.—Before going into the actual operation of the system illustrated in Figs. 2A and 2B let us first observe that the contact 360 of the out-of-correspondence relay 8TER is normally shunted by the following shunting circuit: beginning at the left-hand terminal of the contact 360, front contact 380 of the switch control relay 8WN, polar contact 381 of switch repeating relay 8WP, back contact 382 of the signal control relay 4GZ, back contact 384 of the signal relay 4AG, back contact 385 of the signal relay 4BG, back contact 386 of the signal control relay 5GZ and back contacts 387 and 388 of the signal relays 5AG and 5BG, respectively, and then to the opposite side of the contact 360. By the careful study of these contacts together with the contacts 390 of switch control relay 8WR, 391 of signal relay 5AG, and 392 of signal relay 4AG, it will be seen that any out-of-correspondence condition between the switch control relay and signal control relays and the switch repeater relay and signal relays which they control will cause this shunting circuit to be opened. In other words, these contacts perform the same functions for a plurality of devices that the contacts 363, 364, 362, and 361 for the single track switch of the Fig. 1 structure perform.

Let us now assume that the operator in the central office wishes to clear the signal 4A and in order to do so he moves his signal control lever 4-5SGL into its right-hand dotted position. This movement of the signal lever causes momentary closure of the circuit starting at the terminal (-), contact 394 of the signal control lever 4-5SGL, back contact 368 of the station relay 8ST to the winding of the out-of-correspondence relay 8OCR. The operator upon depressing his starting button 8SB will initiate the system into operation and will cause a code to be transmitted to the field station shown in Fig. 2B. The first portion of this code will select that field station and the second portion of this code will, among other things, cause energization

of the signal control relay 4GZ. The moment that this signal control relay is energized, it will be stuck up through a stick circuit starting from the terminal (+) of a suitable battery through front contact 395 of track relay 8TR, back contact 396 of the signal stop relay 4-5B and through stick contact 397. With the signal control relay 4GZ now energized a circuit for the heating coil of the thermal relay 8TE, which may be traced as follows, is closed: beginning at the terminal (+) of a suitable source of current, front contact 400 of the signal control relay 4GZ, back contact 401 of the signal relay 4AG, back contact 402 of the signal relay 4BG, heating coil of the thermal relay 8TE and through back contact 358 of the out-of-correspondence transmitting relay 8TER to the other terminal minus (-) of the same source of current. If there is no train directly ahead of the signal 4A, the circuit for the signal relay 4AG and including the front contact 404 of the relay 4GZ, the front contact 405 of the switch repeating correspondence relay 8NCR and the front contact 406 of the home-distant relay 4H will be closed. The signal relay 4AG will under the assumed condition be immediately picked up and will open the energizing circuit for the heating coil of the time element relay 8TE at the back contact 401 of signal relay 4AG. Thermal relay 8TE will have its energizing circuit broken at the back contact 401 of this signal relay 4AG. If, however, we assume that there is a train directly ahead of the signal 4A but beyond the detector track circuit including track relay 8TR and that the home relay 4H is for this reason deenergized, it will be seen that the back contact 401 of the signal relay 4AG remains closed and that the thermal relay 8TE is energized. If this condition of energization of the thermal relay 8TE is continued for a predetermined time sufficient to allow the particular signal or the switch machine to have completed its operation, this thermal relay 8TE will close its contact 354 and in so doing will complete a pick-up circuit for the out-of-correspondence transmitting relay 8TER. The completion of this pick-up circuit will, of course, cause the relay 8TER to assume its energized position thereby closing its stick circuit moving its contact 360 from its back point to its front point and since this contact 360 is no longer shunted, the circuit through the front contact 382 of the relay 4GZ being open at front contacts 392 and 385 of the relays 4AG and 4BG, respectively, the stick circuit for change relay 8CH is broken; that is, with contact 360 of the relay 8TER unshunted, its movement from its back point to its front point will cause momentary deenergization of the change relay 8CH thereby causing this change relay to drop and close its back contact 154 which causes initiation of the code type selector apparatus. Since the front contact 366 of the out-of-correspondence transmitting relay 8TER is now closed a code will be transmitted to the central office shown in Fig. 2A, the first portion of which causes energization of the station relay 8ST and the second portion of which causes the out-of-correspondence relay 8OCR to be operated to its left-hand polar position to light the out-of-correspondence lamp 8OCL. This will, of course, inform the operator that his movement of the signal lever 4-5SGL has resulted in an out-of-correspondence condition as between the control relay which this lever controls and the

signal relay which such signal control relay controls, and the operator will be informed that his signal 4A did not clear.

In a similar manner the failure of the switch machine or some other signal to operate in time in response to a change in the position of its control lever will cause the out-of-correspondence lamp 8OCL to be illuminated to inform the operator of this fact.

The applicant has thus devised a remote control and indication system of the code communication type in which the positions assumed by the control levers, when interpreted in the light of the condition of an out-of-correspondence indicator, may be ascertained without transmitting by code either the position assumed by the device controlled by such lever or the fact that it is in correspondence with such lever. That is an indication, namely an out-of-correspondence indication, is only transmitted when an abnormal and unusual condition exists at the field station. By this construction very few indications need be transmitted by the code type communication system as a result of which a larger number of control codes may be transmitted without overloading the system. It is desired to be understood, however, that the particular system shown and described does not exhaust all forms the invention may take, and that the particular form shown has been selected to facilitate illustration and description of the invention, and it should further be understood that various changes, additions and alterations may be made to adapt the invention to the particular problems encountered in practicing the same all without departing from the spirit of the invention except as demanded by the scope of the appended claims.

What I claim as new is:

1. In a centralized traffic controlling system for railroads, in combination with a section of railway track at a field station including a track switch, a switch machine for operating said track switch, a detector track circuit associated with said track switch, a signal for governing traffic over said track switch, two electro-responsive devices one for controlling said switch machine and the other for controlling said signal, a switch control lever and a signal control lever at a control office, a correspondence indicator and a track indicator at said office, a time element device at said field station controlled by a circuit which is closed only if said track switch or said signal is out of correspondence with its respective electro-responsive device and rendered active a time after closure of its circuit which is greater than the time required for said switch machine or said signal to be operated, and a code type communicating system connecting said office and said field station for controlling said electro-responsive devices in accordance with the positions assumed by their respective control levers and for controlling said non-correspondence indicator and said track indicator respectively in accordance with whether said time element device is active or inactive and whether said detector track circuit is occupied or unoccupied, whereby if the non-correspondence indicator is active and said track indicator is inactive such condition may be taken as an indication that another track circuit capable of putting said signal to stop is occupied.

2. In a centralized traffic controlling system for railroads, in combination with a section of railway track at a field station including a track switch, a switch machine for operating said track

switch, a detector track circuit associated with said track switch, a signal for governing traffic over said track switch, two electro-responsive devices one for controlling said switch machine and the other for controlling said signal, a switch control lever and a signal control lever at a local office, a normally inactive non-correspondence indicator and a track indicator at said office, a time element device controlled by a circuit which is closed only if said track switch or said signal is out of correspondence with its respective electro-responsive device and rendered active a time after closure of its circuit which is greater than the time required for said switch machine or said signal to be operated, and a code type communicating system connecting said office and said field station for controlling said electro-responsive devices in accordance with the positions assumed by their respective control levers and for controlling said non-correspondence indicator and said track indicator respectively in accordance with whether said time element device is active or inactive and whether said detector track circuit is occupied or unoccupied, and means responsive to the movement of either of said levers to another position for restoring said non-correspondence indicator to normal, whereby if the non-correspondence indicator is active and said track indicator is inactive such condition may be taken as an indication that another track circuit capable of putting said signal to stop is occupied.

3. In a centralized traffic controlling system for railroads, in combination with a section of railway track at a field station including a track switch, a switch machine for operating said track switch, a detector track circuit associated with said track switch, a plurality of signals for governing traffic over said track switch, a plurality of electro-responsive devices one for controlling said switch machine, and one for each direction of traffic controlled by said signals, a switch control lever and a signal control lever at a local office, a non-correspondence indicator and a track indicator at said office, a time element device controlled by a circuit which is closed only if said track switch or any one of said signals is out of correspondence with its respective electro-responsive device and rendered active a time after closure of its circuit which is greater than the time required for said switch machine or any one of said signals to be operated, and a code type communicating system connecting said office and field station for controlling said electro-responsive devices in accordance with the positions assumed by their respective control levers and for controlling said non-correspondence indicator and said track indicator respectively in accordance with whether said time element device is active or inactive and whether said detector track circuit is occupied or unoccupied, whereby if the non-correspondence indicator is active and said track indicator is inactive such condition may be taken as an indication that another track circuit capable of putting a signal to stop is occupied.

4. In a centralized traffic controlling system of the code type, in combination with an office and a field station, a code communicating system connecting said office and field station including a change relay normally energized by a stick circuit and located at said field station for when deenergized initiating the transmission of a code from said field station, a traffic controlling device at said field station, a lever at the control office for controlling said electro-responsive means through the medium of said communicating sys-

tem, an out-of-correspondence relay at said field station energized after a period of delay in response to actuation of said electro-responsive means out of correspondence with said traffic controlling device, a contact controlled by said out-of-correspondence relay and included in said stick circuit for momentarily opening said stick circuit to drop said change relay in response to a change in the position assumed by said out-of-correspondence relay, and a shunting circuit for bridging said contact closed only if said electro-responsive means and said traffic controlling device assume corresponding positions.

5. In a centralized traffic controlling system of the code type, in combination with an office and a field station, a code communicating system connecting said office and field station including a change relay normally energized by a stick circuit and located at said field station for when deenergized initiating the transmission of a code from said field station, a plurality of traffic controlling devices at said field station, an electro-responsive means at said field station for each of said traffic controlling devices to control the same, a lever in said office for controlling said electro-responsive means through the medium of said communicating system, an out-of-correspondence relay at said field station energized after a period of delay in response to actuation of any one of said electro-responsive means out of correspondence with its traffic controlling device, a contact controlled by said out-of-correspondence relay and included in said stick circuit for momentarily opening said stick circuit to drop said relay in response to a change in the position assumed by said out-of-correspondence relay, and a shunting circuit for bridging said contact and closed only if all of said electro-responsive means and their associated traffic controlling devices assume corresponding positions.

6. In a centralized traffic control and indication system of the code type; in combination with a stretch of track; a traffic controlling device for said stretch; a control relay for controlling said traffic controlling device; code communicating apparatus including an office, a field station, office coding apparatus at said office and field coding apparatus at said field station connected by line wires for transmitting control codes from said office to said field station and transmitting indication codes from said field station to said office, such apparatus being normally at rest; an out-of-correspondence relay which if energized initiates said code communication apparatus and transmits an out-of-correspondence code to said office; a time element device, having an energizing circuit closed so long as said traffic controlling device and said control relay assume out-of-correspondence conditions and rendered active if said energizing circuit is closed for more than a predetermined period of time and restored to normal if said energizing circuit is broken before the lapse of said predetermined time, for when active energizing said out-of-correspondence relay; means effective when said out-of-correspondence relay assumes its energized position and initiates said apparatus for transmitting an out-of-correspondence code to said office; and an out-of-correspondence indicator at said office rendered active in response to the transmission of an out-of-correspondence code from said field station to said office.

7. In a coded centralized traffic control system for railroads for governing a power track switch at one of a plurality of field stations each remote

from a control office, manually operable means at the control office having normal and reverse positions, electro-responsive means at the field station having normal and reverse positions, code communication means for operating said electro-responsive means in correspondence with the respective normal and reverse positions of said manually operable means, circuit means at the field station responsive to said electro-responsive means for causing the power operation of said track switch to a normal or a reverse position in correspondence with such electro-responsive means, an out-of-correspondence indicator at the control office, and code communication means, including time controlled means and a separate source of energy for the time controlled means, for communicating a control from the field station to the control office for the energization of said indicator when said track switch is out of correspondence with said electro-responsive means, such communication means being effective to communicate a control for the energization of said indicator only if said track switch has been out of correspondence with said electro-responsive means for a period of time longer than that normally required for the power operation of that track switch whereby to make the code communication means available during the time of temporary "out-of-correspondence" conditions, for other communication use, and to prevent unnecessary use of the code communication means.

8. In a coded centralized traffic control system for railroads for governing a power track switch at one of a plurality of field stations each remote from a control office, manually operable means at the control office having normal and reverse positions, electro-responsive means at the field station having normal and reverse positions, code communication means for operating said electro-responsive means in correspondence with the respective normal and reverse positions of said manually operable means, circuit means at the field station responsive to said electro-responsive means for causing the power operation of said track switch to a normal or a reverse position in correspondence with such electro-responsive means, an out-of-correspondence indicator at the control office, code communication means for communicating a control from the field station to the control office for the energization of said indicator when said track switch is out of correspondence with said electro-responsive means, such communication means including a time controlled device and a separate source of energy to energize said device, and being effective to communicate a control for the energization of said indicator only if said track switch has been out of correspondence with said electro-responsive means for a period of time longer than that normally required for the power operation of that track switch, whereby to make the code communication means available during the time of temporary "out-of-correspondence" conditions, for other communication use, and to prevent unnecessary use of the code communication means and circuit means at the control office for deenergizing said indicator upon movement of said manually operable means from one operating position to the other.

9. In a coded centralized traffic control system for railroads for governing a power track switch at a field station remote from a control office, manually operable means at the control office having normal and reverse positions, electro-re-

sponsive means at the field station having normal and reverse positions, code communication means for operating said electro-responsive means in correspondence with the respective normal and reverse positions of said manually operable means, circuit means at the field station responsive to said electro-responsive means for causing the power operation of said track switch to a normal or a reverse position in correspondence with such electro-responsive means, an out-of-correspondence indicator at the control office, and code communication means for communicating a control from the field station to the control office for the energization of said indicator when said track switch is out of correspondence with said electro-responsive means, such communication means being effective only if said track switch has been out of correspondence with said electro-responsive means for a longer than normal period of time, and such communication means being effective in response to operation of the manual means to a new position and after the expiration of said longer than normal period of time, to communicate another control to cause the de-energization of said indicator subsequent to its energization at the end of said longer than normal period of time.

10. In a coded centralized traffic control system for railroads for governing a power track switch at a field station remote from a control office, manually operable means at the control office having normal and reverse positions, electro-responsive means at the field station having normal and reverse positions, code communication means for operating said electro-responsive means in correspondence with the respective normal and reverse positions of said manually operable means, circuit means at the field station responsive to said electro-responsive means for causing the power operation of said track switch to a normal or a reverse position in correspondence with such electro-responsive means, an out-of-correspondence indicator at the control office, code communication means for communicating a control from the field station to the control office for the energization of said indicator when said track switch is out of correspondence with said electro-responsive means, such communication means being effective to communicate a control for the energization of said indicator only if said track switch has been out of correspondence with said electro-responsive means for a longer than normal period of time, and such communication means being effective to communicate another control to cause the deenergization of said indicator subsequent to its energization at the end of said abnormal period, upon movement of said manual means to a new position and subsequent to the expiration of said longer than normal period of time, and circuit means at the control office for deenergizing said indicator, if it be then energized, upon the manual operation of said manually operable means from one operating position to the other.

11. In a coded centralized traffic control sys- 65

tem for railroads for governing the clear and stop indications of a signal at any one of a plurality of field stations remote from a control office, manually operable means at the control office for said signal having distinctive stop and clear operating positions, electro-responsive means at the field station for said signal having distinctive clear and stop positions, code communication means for operating said electro-responsive means to positions corresponding to those of said manually operable means at the control office, circuit means at the field station responsive to said electro-responsive means for causing said signal to indicate clear or stop in accordance with the manner in which said electro-responsive means is conditioned, an out-of-correspondence indicator at the control office, and code communication means for communicating a control from the field station to the control office for the energization of said indicator when said signal is out of correspondence with said electro-responsive means, such means being effective to communicate that control only if said signal has been out of correspondence with said electro-responsive means for a period of time greater than that normally required for response of that signal to the positioning of said electro-responsive means.

12. In a coded centralized traffic control system for railroads for governing the clear and stop indications of a signal at a field station remote from a control office, manually operable means at the control office for said signal having distinctive stop and clear operating positions, electro-responsive means at the field station for said signal having distinctive clear and stop positions, code communication means for operating said electro-responsive means to positions corresponding to those of said manually operable means at the control office, circuit means at the field station responsive to said electro-responsive means for causing said signal to indicate clear or stop in accordance with the manner in which said electro-responsive means is conditioned, an out-of-correspondence indicator at the control office, code communication means for communicating a control from the field station to the control office for the energization of said indicator when said signal is out of correspondence with said electro-responsive means, such means being effective to communicate that control only if said signal has been out of correspondence with said electro-responsive means for a period of time greater than that normally required for the response of such signal, and such communication means being effective in response to operation of the manual means to a new position and subsequent to the expiration of said greater than normal period of time, to communicate another control from the field station to the control office to cause the deenergization of said indicator subsequent to its energization at the end of such abnormal period.
